UNITED STATES PATENT OFFICE.

GEORG GRABE, OF NIKOLASSEE, NEAR BERLIN, GERMANY, ASSIGNOR TO SIEMENS & HALSKE, A. G., OF BERLIN, GERMANY, A CORPORATION OF GERMANY.

TELEPHONE SYSTEM.

1,343,714.

Specification of Letters Patent. Patented June 15, 1920.

Application filed January 14, 1915, Serial No. 2,233. Renewed November 6, 1919. Serial No. 336,232.

To all whom it may concern:

Be it known that I, GEORG GRABE, a citizen of the German Empire, and residing at Nikolassee, near Berlin, Germany, have 5 invented certain new and useful Improvements in Telephone Systems, of which the following is a specification.

This invention relates to automatic or semi-automatic telephone exchange systems 10 and particularly to exchanges operated by selecting switches connected to a plurality of groups of trunk lines and set by means of a continuous actuating driving force operable in only one direction.

15 The primary object of the invention is to provide an improved organization of circuits and apparatus by which the selective connection of two subscribers' instruments may be accomplished more rapidly and with 20 greater certainty, than heretofore.

Another object of the invention is to adapt such selecting switches to be operated by means of number impulses and to attain a high speed for the setting operation of such 25 switches.

For this purpose the selecting switches are started by a driving mechanism which is controlled by number impulses generated in an impulse circuit, whereas the movement of 30 the switches is stopped by another preferably a testing circuit.

In the drawings, Figures 1 and 2 show a circuit diagram illustrative of the mode of operation of the exchange.

35 Fig. 3 is a detail view of an escapement mechanism used in connection with the driving mechanism (not shown) of the connector switches.

40 Fig. 4 is a side elevation of a driving mechanism adapted for use in connection with selector switches or connector switches, the escapement shown in this figure being for a selector switch.

45 For the sake of clearness only such portions of the circuits and apparatus have been illustrated as are requisite for understanding the invention.

It is deemed advisable to proceed with a 50 description of the circuits and mode of operation of the system, whereas details of mechanism will be described later.

The circuits are illustrated by Figs. 1 and 2, wherein N diagrammatically represents a

calling station, VW a line switch, GW a selector and LW a connector.

The operation of the system is as follows:

When the subscriber at the calling station N takes off the receiver, the following circuit is closed: ground, battery, first exciting coil of the call relay Ra, contact 1t, 55 subscriber's line a', contact i, receiver hook, subscriber's line b', contact 2t, second exciting coil of the call relay Ra, ground. In this circuit the call relay Ra is energized causing the wipers of the line switch VW 60 to advance to idle terminals of a selector GW. As soon as the wipers of the line switch VW engage idle terminals of a selector GW a current is caused to flow from ground through battery, contact 3ra which 65 is closed by the relay Ra, relay T, trunk line c1, normal contact k1 to ground. The relay T which is energized in the said circuit will 70 detach at the contacts 1t, 2t the relay Ra from the subscriber's lines a', b' and extend 75 the connection to the trunk lines a1, b1. The contact 4t which is closed by the relay T will short circuit the high resistance winding of the relay T and, at the same time, maintain the other winding of the relay T excited. 80 Thus, the engaged trunk line of the selector GW will be locked against seizure. The connection being extended to the trunk lines a1, b1 the relays A, B are energized in a circuit over contacts 5e, 6e, whereas the relay 85 X in this circuit being a differentially wound relay will remain deenergized.

If now at the subscriber station N the dial F₈ is turned in the direction of the arrow, the contact ek is closed. Thus, the subscriber's lines a', b' of the talking connection are simultaneously grounded. The differentially wound relay X will become excited thereby and close its contact x, so that the relays A, B remain energized. The dial F₈ 90 having been set and released, the number impulses are generated by correspondingly making and breaking the contact i. At each interruption of the current at contact i the relay A of the selector GW is momentarily 95 deenergized whereas the relays B and X remain excited. As soon as the selector GW leaves its normal position the normal contact k1 is opened and the contact 7b closed by the relay B. This relay also closes the contacts 100 8b and 9b, whereby on the one hand, the

electromagnet R is energized and, on the other hand, a circuit prepared through the locking relay S. The relay A closes the contact 10a, whereby the relay S will be energized in the circuit from ground through battery, relay S, normal contact k2, contact 10a to ground. The relay A also closes the contact 11a and then opens the back contact 12a.

16 When idle fixed terminals of the selector GW are engaged by the wipers of the line switch VW, the relays A and B become simultaneously energized and the contacts 8b and 10a closed, so that the relays R and S simultaneously respond to the exciting current. At this operation the wipers a, b, c, d remain in their normal position 0. As soon as the relay X becomes excited the back contact 13a is opened and the working contact 14a closed, whereby the operation of the relay S becomes dependent upon the position of the contacts 10a and 12a. The wipers a, b, c, d, however, leave their normal position only at the time the number impulses are sent out.

We will suppose that the subscriber at the station N has sent out only a single impulse as the first of a series of number impulses. Thus, the relay A will be once deenergized, 39 the back contact 12a closed and thereafter the working contact 11a opened. At the same time the contact 10a will be opened and the current through the relay S will cease so that the wipers a, b, c, d will be moved 35 from their normal position 0 to the contacts 00. If the back contact 12a is closed the wipers a, b, c, d engaging the contact 0 will after a short stop be moved to the contacts 00; should, however, at the time the 40 back contact 12a be open said wipers will be moved at once to the contacts 000. In this position the relay S will be reenergized over the working contact 11a and the wipers remain in their position until the relay A 45 will become excited again. As soon as the wipers move out of their normal position 0 the normal contacts k1, k2 will be opened and the contact k3 be closed. By the opening of the contact k2 the influence of the contact 10a 50 on the relay S will cease. When now the relay A is again energized, the circuit through the relay S will be broken at the working contact 11a. The wipers will then be moved a further step and an idle trunk line be selected from the first group of contacts which are connected with trunk lines leading to other selectors. The testing is accomplished by the relay S in such a manner that, if the dial F_s returns to its normal position, the 55 relay X will become deenergized whereby the testing circuit of the relay S over the testing wiper c will be closed at the back contact 13a. The relay S becomes energized as soon as the wiper c engages the terminal 60 of an idle trunk line c2. A busy trunk line

will not allow of an energization of the relay S since the relay C of the following selector is energized and thereby a resistance w1 included in the circuit.

When the wipers a, b, c engage the terminals of the trunk lines a2, b2, c2 the relay S of the selector GW and in series therewith the relay C at the following selector are energized, the current flowing from ground through battery, relay S, contact 13a, retarding relay E, contact 9b, wiper e, trunk line c2, contact 15a, relay C, contact 16a to ground. The relay C will then close the contact 17a, and include the resistance w1 in the circuit thus locking the trunk line 70 against seizure. The relay S when energized will attract its armature and stop the wipers of the selector on the guarded trunk line. The talking connection will then be extended over contacts 18a, 19a to the trunk 75 lines a2, b2. Simultaneously with the relay S the relay E is energized which detaches the relays A, B, X from the talking line by opening the contacts 5a, 6a. The relay E closes the contact 20a and establishes a circuit 80 for the relays S, E and C independently of the contact 9b which will be opened as soon as the relay B is detached from the talking line by breaking the contact 6a. The relay S closes the contact 21a and establishes another circuit for the relay T of the line switch VW.

If, however, for setting the selector GW a plurality of number impulses in series for instance two are sent out by the calling station N the wipers a, b, c of the selector GW are moved after the first impulse to the contacts 000, after the second impulse to the contacts a⁰⁰, b⁰⁰, c⁰⁰, d⁰⁰ and so on, whereupon the automatic selection of an idle terminal takes 100 place in the desired group of trunk lines. We will suppose that for setting the selector GW two impulses have been sent out. As already explained, the wipers a, b, c reach the contacts 000, if after the first impulse 105 the relay A is again reenergized. Before, however, the relay X is deenergized and the wipers are automatically operated thereby, the relay A is temporarily deenergized and reenergized for the second impulse. If at 110 this time the relay A is deenergized the circuit over the working contact 14a is broken at the back contact 12a. The relay S, therefore, releases its armature, and the wipers are turned a further step. If the wipers 115 reach the contacts a⁰, b⁰, c⁰, d⁰ before the back contact 12a is broken, they remain in the position until the contact 12a is open, whereupon they are moved to the contacts a⁰⁰, b⁰⁰, c⁰⁰, d⁰⁰. Should, however, the back 120 contact 12a be broken when the wipers engage the contacts a⁰, b⁰, c⁰, d⁰ the wipers will at once be turned to the contacts a⁰⁰, b⁰⁰, c⁰⁰, d⁰⁰. If then the relay A is again energized 125 and the working contact 11a closed the auto- 130

matic selection of an idle terminal in the second group of trunk lines at the selector GW takes place. For this purpose the relay S is cut into the testing circuit over the back contact 13a by breaking the contact ek at the subscriber's station N when the dial returns to its normal position so that the relay X is deenergized before the back contact 12a is broken by the reenergization of the relay A.

10 If after conversation the connection is released the contact 15m at the selector subsequent to the selector GW will be opened and the circuit for the relays C, E and S broken. The relay E being slow acting will release its armature only after the selector GW has reached its normal position of rest 0. The selector GW is moved into this position as soon as the relay S becomes deenergized, so that its armature is released. The rotary 20 movement of the selector GW continues until the armature of the electromagnet R is released. This operation takes place if the wiper c engages the contact 0, the contact k3 as well as the circuit through the electromagnet R being broken at the same time.

25 In order to prevent a rotation of the selector GW to the succeeding group of terminals, if all terminals in a tested group are busy, additional contacts a^{**0} , b^{**0} , c^{**0} , d^{**0} are provided between two succeeding groups of terminals. If all terminals in a group preceding said additional contacts are busy, the wipers stop at the said additional contacts. If, for instance, the wiper c engages the additional contact c^{**0} , the following circuit is established through the relay S: ground, battery, relay S, back contact 13e of relay X, relay E, working contact 9b, wiper c, contact c^{**0} , resistance $w2$ to ground.

40 Referring now to Fig. 2 the operation of the connector is as follows:

If the fixed terminals of the connector LW are engaged by the movable terminals of a selector GW the relay A'' bridged across the talking lines will be energized. The contact 30a'' is now closed and the relay V1 which is slow acting will be energized so that the contact 31v1 is closed and the electromagnet R' excited. By this operation the lock of the 50 armature of the relays S' and F is released (Fig. 3). Said armature can, however, not be moved since the relay S' is simultaneously excited with the relay R', the circuit extending from ground over contact 32a'', normal contact k6, first exciting coil of the relay S', normal contact k7, battery, to ground. If now the first series of number impulses for setting the connector LW is sent out—and which series may be supposed to consist of 60 two impulses—the wipers a^* , b^* , c^* , d^* are moved in the same manner as already described with reference to Fig. 1 until after the second impulse they engage the contacts a^{**0} , b^{**0} , c^{**0} , d^{**0} . This setting of the 65 wipers being accomplished by deenergizing

and reenergizing the impulse relay A'' and operating the contacts 11a'' and 12a'' controlled by the relay A'' in a similar manner as the contacts 11a and 12a of Fig. 1. While the impulses are being sent out the relay V2 70 is energized by a circuit from ground through battery over contact p, relay V2, contacts 34v1, 33a'' to ground, and holds its armature attracted which will be released only after sometime is elapsed after the last 75 impulse of the series. Since the relay V2 is slow acting the contact 35v2 will be broken, so that an energization of the relay U is prevented. If after completion of the series of number impulses the relay A'' becomes excited for a longer period and the armature of the relay V2 is released, this relay will close its contact 35v2 and excite the relay U. The relay U by closing its contact 36u remains excited independently of the condition of 85 the relays V2 and A''.

When the second series of number impulses is being sent out and the relay A'' deenergized, the relay V2 becomes again excited and holds its armature attracted until 90 the sending out of the number impulses is completed. Since, however, during this operation the relay U is energized a circuit for the relay F and the second exciting coil II of the relay S' is established over the contacts 95 37a'' and 38u. The exciting coil I of the relay S', which is differentially wound to the exciting coil II, will be energized as soon as the relay U is excited and the contacts 39u, 40v1 and 41v1 are closed. This exciting 100 coil I of the relay S' remains energized until the connector LW is released. If the second series of number impulses is sent out and the relay A'' is deenergized the exciting coil II of the relay S' as well as the relay F will be 105 excited over the closed contact 37a''. The differential relay S' will now release its armature so that this armature may be attracted by the relay F (see Fig. 3) and the wipers of the connector may be moved half 110 the way from contacts a^{**0} , b^{**0} , c^{**0} , d^{**0} to the next succeeding contacts. These latter contacts will be reached by the wipers as soon as the relay A'' is reenergized, the circuit through the exciting coil II of the relay S' 115 and the relay F being broken again at contact 37a'' so that the armature may be again attracted by the relay S'. In the same manner the wipers are moved by each impulse to the next contact so that for instance by five 120 number impulses the wipers will be moved to the terminals of the lines a3, b3 of the called subscriber. After having sent out the last number impulse the relay V2 will hold its armature still attracted for a certain period. 125 During this period the connection to the called subscriber will be tested. If the terminal of the line to the called subscriber is idle a circuit will be established extending from ground through battery, both coils in 130

series of the test relay P over contacts 42v1, 43v2, 44u, wiper c*, subscriber's line c3, normal contact 45h1, through both exciting coils of the relay T' off normal contact 46h' to ground. The relays P and T' are energized in this circuit, and the contacts 47p, 48p closed, so that the relay P remains energized independently of the condition of the relay V2 and the subscriber's line will be made busy by closing the contact 48p which short circuits the exciting coil II of the relay P. The energized relay P closes the contact 49p and cuts into circuit the ringing relay L. The excited relay L will close its contacts 50¹ and 51¹ and apply ringing current over the contacts 52p and 53p of the relay P to the called subscriber's lines a3, b3.

When the called subscriber takes off his receiver, the relay Y becomes energized. This relay will open the contact 54y and thus cut the relay L out of circuit. Thereby the ringing current will be broken whereas the talking connection is now complete.

Should the called subscriber's station be busy the relay P will not be energized, since the line switch VW' is not in its normal position and, therefore, the normal contact 45h1 broken, if in the established connection the said subscriber was the calling subscriber. If, however, the subscriber had been called the relay P will not get sufficient energy, since the test relay of the connector is short-circuited.

If after conversation the established connection is released by replacing the receiver at the calling station N the relay A'' as well as the relay V1 will become deenergized. Thus the contacts closed by the relay V1 will be broken and thereby the relays U, S' and P deenergized. The relay R', however, remains still excited for a short period since the normal contact h4 is closed. As soon as the armature of the relay S' is released the wipers of the connector LW will be rotated until they reach their normal position "0" in which the circuit for the relay R' is broken at the normal contact h4.

Fig. 4 shows in detail the driving mechanism adapted for use in connection with selector switches or connector switches. The escapement illustrated in this figure is constructed for a selector switch.

On the shaft 61 is loosely mounted a ratchet wheel 62 which is rigidly connected with a drum 63. A coiled spring is connected at its one end 64 with the drum 63 and with its other end at 65 with the shaft 61 or with a disk 66 mounted on the shaft. On the drum 63 is provided a closed contact ring 67 which is insulated from the drum 63 and engaged by a contact brush 68. The contact ring 67 is provided with another contact brush 69 which engages another contact ring 71 having an opening at 70. This second contact ring 71 is mounted on and in-

sulated from a gear wheel 72 rigidly connected with the shaft 61. An electric connection 73 is provided between the contact ring 71 and a collector ring 74 which is insulated from the shaft 61. This collector ring 74 is engaged by a brush 75. The ratchet wheel 62 is actuated by a pawl 76 operated by an electromagnet 77 with automatic break. Instead of the automatic break contact there may of course be provided a cut-out of the normal type. The backward movement of the ratchet wheel 62 is prevented by a pawl 80. The gear wheel 72 meshes with a pinion 82 which is mounted on a shaft 81 together with an escapement wheel 83 and two pairs of selector wipers 84, 85. The selector wipers engage with two series of contacts which are arranged the one above the other. The escapement 86 is connected with a lever 87 which serves as an armature of the test relay S. This lever is locked in its normal position by a detent at the armature 88 of the call relay R.

If for setting the selector the call relay R is energized, the lock of the escapement 86 will be released so that the spring of the driving mechanism will cause by means of the gearing 72, 82 a step by step movement of the selector wipers 84, 85. During this movement the coiled spring provided in the drum 63 will be partly released from tension so that the contact brush 69 engages the contact ring 71. The circuit for the electromagnet 77 will be extended from ground through brush 68, contact ring 67, brush 69, contact ring 71, connection 73, collector ring 74, brush 75, conductor 98, electromagnet 77, contact spring 99, battery to earth. The ratchet pawl 76 will move the ratchet wheel 62 so that the coiled spring will be wound up. This winding up takes place until the brush 69 reaches the opening or recess 70 whereby the exciting circuit for the electromagnet 77 is broken.

When the wiper 84 or 85 engages the desired contact, the test relay S will be energized and stop the movement of the selector wipers by attracting its armature, whereas the driving mechanism is operated until the spring is wound up again or the operating circuit broken. The interrupter operates so quickly that the selector is constantly operable.

The selector may also be operated without the gearing 72, 82, shown. In this case the selector wipers will be provided on the shaft 61 and the gear wheel 72 formed as an escapement wheel.

I claim:

1. A telephone exchange system, comprising trunk lines arranged in a plurality of groups, a switch, a driving mechanism therefor, an impulse circuit to set said switch on a desired group of trunk lines, said impulse circuit starting the movement of said switch

- by means of said driving mechanism, and another circuit to stop said movement once for each impulse in said impulse circuit. 65
2. A telephone exchange system, comprising trunk lines arranged in a plurality of groups, a switch, a driving mechanism therefor, an impulse circuit to set said switch on a desired group of trunk lines, said impulse circuit starting the movement of said switch by means of said driving mechanism, a testing circuit to stop said movement once for each movement in said impulse circuit, and special contacts located between the contacts of said groups of contacts for closing said 70 testing circuit.
3. A telephone exchange system, comprising trunk lines arranged in a plurality of groups, each group comprising a plurality of trunk lines, a switch, driving mechanism therefor, an impulse circuit to set said switch on a desired group, said impulse circuit starting the movement of said switch by means of said driving mechanism, another circuit to stop said movement and a third circuit causing said switch to select an unoccupied trunk line out of said plurality of trunk lines of said desired group. 75
4. A telephone exchange system comprising trunk lines arranged in a plurality of groups, each group comprising a plurality of trunk lines, a switch, a driving mechanism therefor, an impulse circuit to set said switch on a desired group, said impulse circuit starting the movement of said switch by means of said driving mechanism, a second circuit to stop said movement, a third circuit causing said switch to select an unoccupied trunk line out of said plurality of trunk lines in said desired group, and means to prevent said switch to select an unoccupied trunk line in a different group of trunk lines, when all trunk lines of said desired group are occupied. 80
5. A telephone exchange system, comprising trunk lines arranged in a plurality of groups, a switch, a driving mechanism therefor, an impulse circuit to set a switch on a desired group, said impulse circuit starting the movement of said switch by means of said driving mechanism, a second circuit to stop said movement once for each movement in said impulse circuit, and means to re-arrange said circuits to receive a second series of impulses in said impulse circuit to set said switch on a particular line in said desired group. 85
6. A telephone exchange system, comprising trunk lines arranged in a plurality of groups, a switch, a spring actuated driving mechanism therefor, means to restore the tension of said spring, when reduced by the movement of said switch, an impulse circuit to set said switch on a desired group, said impulse circuit starting the movement of 90
- 95
- 100
- 105
- 110
- 115
- 120
- said switch by means of said driving mechanism, and another circuit to stop said movement. 65
7. A telephone exchange system, comprising trunk lines arranged in a plurality of groups, a switch, spring actuated driving mechanism therefor, an impulse circuit to set said switch on a desired group, said impulse circuit starting the movement of said switch by means of said driving mechanism, a testing circuit to stop said movement of said switch, and electromagnetically operated means to restore the tension of said spring, and circuits to start and stop said restoring means. 70
8. A telephone exchange system, comprising trunk lines arranged in a plurality of groups, a switch, spring actuated driving mechanism therefor, an impulse circuit to set said switch on a desired group, said impulse circuit starting the movement of said switch by means of said driving mechanism, a testing circuit to stop said movements, electromagnetically operated means to restore the tension of said spring, circuits to start and stop said restoring means, said circuits starting said restoring means with the beginning of the movement of said switch and said circuit stopping said restoring means when the tension of said spring is restored. 85
9. A telephone exchange system, comprising trunk lines arranged in a plurality of groups, a switch, spring actuated driving mechanism therefor, an impulse circuit to set said switch on a desired group, said impulse circuit starting the movement of said switch by means of said driving mechanism, a testing circuit to stop said movement, electromagnetically operating means to restore the tension of said spring, said means comprising a pawl and ratchet, a solenoid and a core passing through said solenoid, one end of said core being attached to the ratchet of said restoring means, the other end being attached to a spring controlling the extent of the movement of said core. 90
10. A telephone exchange system, comprising a switch, a spring actuated escapement wheel therefor, an oscillatory escapement, circuits to start and stop the movements of said escapement, electromagnetically operated means to restore the tension of said spring, comprising a solenoid and an oscillatory core for driving said restoring means, said escapement and restoring means being independent from each other. 100
